(57) **CLAIM**

The ornamental design for a battery charger for digital cameras, as shown and described.

DESCRIPTION

FIG. 1 is a top, front and side perspective view of a battery charger for digital cameras, showing my new design;
FIG. 2 is a front elevational view thereof;
FIG. 3 is a rear elevational view thereof;
FIG. 4 is a top plan view thereof;
FIG. 5 is a bottom plan view thereof; and,
FIG. 6 is a side elevational view thereof from the left of FIG. 2, the side opposite that shown in FIG. 6 being the mirror image thereof.
